SHOE SHAPING MACHINE

John B. Hadaway, Swampscott, Mass., assignor
to United Shoe Machinery Corporation, Paterson, N. J., a corporation of New Jersey

Application March 28, 1923. Serial No. 628,228

17 Claims. (Cl. 12—17)

This invention relates to machines for use in shaping the soles of boots and shoes, particularly those in which the shaping is done by impact.

Most fine shoes, and particularly those intended to be worn by women, are required to be made with close shanks; that is, the angular space between the upper and outsole, or welt if the shoe is a welt shoe, commonly referred to as the welt crease, must be closed up so that the upper and outsole, or welt, as the case may be, are substantially in contact. During the operation of sewing on the outsole of a welt shoe the welt crease must be open to permit the operation of the sewing instrumentalities in securing the welt and outsole together. The operation of closing the shank is usually performed by hand, a hammer being used to beat or peen the margin of the outsole or edge face of the outsole and cause it to be so shaped and bent that the welt crease is permanently closed.

In case the outsole is channeled to receive the stitches of the outsole sewing machine, it is difficult to direct the blows by hand with such accuracy as to avoid hitting the channel leaf and breaking or otherwise injuring it, and in work that is stitched "aloft", that is, where the stitches are located on the surface of the outsole, hand work leaves much to be desired in the facility and accuracy with which the operation is performed.

Objects of the present invention are to provide mechanical means by which the desired operations may be performed with ease, quickness and precision.

Features of the invention consist in an organization comprising beating means, such as a rotary beater, to which the shoe may be presented while held in the operator's hands, with channel engaging means for guiding the shoe with relation to the beating means as the shoe is moved longitudinally to present different portions of its margin to the beating means. The guiding means preferably serves also to guard and protect the channel leaf from contact with the beating means. The means for guiding the shoe and guarding the leaf is preferably arranged for yielding movement to permit movement of the shoe into engagement with the beater and is preferably rotary to cause as little impedance as possible to longitudinal movement of the shoe. As shown, the guiding and guarding means consists of a roll housed within the end of the beating means and having its periphery contoured to correspond roughly to the

shape of the inturned channel leaf which it is to engage.

An edge gage for determining the lateral position of the work is provided, which gage may, as illustrated, comprise a roll arranged for rotation upon an axis substantially perpendicular to that of the rotary beater. The beater is preferably provided on its periphery with three beating portions, the periphery of the beater being cut away or reentrant between said portions.

In the drawing,

Fig. 1 is a side view of the machine embodying the present invention;

Fig. 2 is a side view of the operating instrumentalities in working position with respect to a shoe shown in section;

Fig. 3 is a view similar to Fig. 2 showing the machine arranged to treat a shoe that is stitched aloft, the shoe being shown in section; and

Fig. 4 is an end view of the pounding tool.

As shown in Fig. 1 of the drawing, a rotary beating tool 2 is mounted on a shaft 4 to be continuously driven at high speed. Conveniently, the shaft 4 may be the armature shaft of an electric motor 6 designed to run at the proper velocity, though, of course, any other suitable means for rotating the shaft may be employed.

To support the work guiding means with which the machine is provided, a stationary sleeve 8 is arranged outside the shaft 4 and may, for example, be fixed to or integral with the casing of the motor 6. On the sleeve 8 a support 10 is fitted to slide or turn, a portion of the support being slit at 12 and provided with a clamp screw 14 by which the member 10 may be clamped in fixed position on the sleeve 8. Pivoted at 16 to the upper portion of the support 10 is an arm 18 the outer portion of which is bent downwardly in front of the beating element 2. The lower portion of the arm 18 is angularly disposed with respect to the shaft 4, and upon the angular portion is pivoted for rotation by a screw 19 a guide roll 20, the axis of the roll being, as shown, at an angle of approximately 30 degrees to the axis of the shaft 4. The roll, longitudinally of its axis, has a reverse curvature, being concave on its periphery near its inner end. The roll 20 is formed with a lip 22 adjacent to its concave portion. The lip 22 is formed and arranged to enter the channel, and the concaved portion of the roll to engage the folded back channel leaf and keep it out of contact with the beating tool 2. In order that a roll of suitable size may be used and the lip of

the roll brought into close relation to the beater, the beater is concaved on its outer face to receive a portion of the roll so that the lip 22 of the roll may be arranged in close proximity to the 5 roll and may, when in working position, have its lip substantially in horizontal alinement with the beating face. The pivot 16 of the arm 18 carrying the roll 20 permits vertical adjustment of the roll, its lower position, in which the lip 22 10 preferably projects slightly below the beater 2, being determined by a screw 24 threaded through the arm and engaging the support 10. To hold the arm and roll so that they may yield upwardly in response to pressure of the shoe upon the 15 roll, a stem 26 is secured to the support 10 and passes upwardly through a hole in the arm 18, a spring 28 being arranged on the stem 26 between the arm 18 and a spring tension adjusting thumb nut 29. 20 Upon the lower side of the support 10 is a holder 30 having a vertical slot through which passes a cap screw 32 threaded into the support. The lower surface of the holder 30 is channeled to receive a curved member or arm 34 (Fig. 3), 25 upon the outer end of which a roll 36 is mounted by a screw 38 to rotate on a vertical axis. The inner end of the member 34 is slotted to receive a cap screw 40 by which it is held in adjusted position to the holder 30. 30 It will be observed that the curved arm 34 is made very thin heightwise along its central portion so that its outer end can yield vertically in case the shoe is tipped far enough to cause the upper of the shoe to engage the roll 36. 35 The roll, therefore, will not interfere with upward pressure of the shoe against the pounding tool, even when tipped to an extreme angular position with respect to the tool.

In the use of the machine, the motor is started 40 to cause the beating tool 2 to be rotated. If a welt shoe having a channel for the outsole seam is to be treated, it is presented as indicated in Fig. 2, the lip 22 of the roll being positioned in the channel and the folded back channel leaf being located in the concave portion of the periphery of the roll. The shoe is then raised to cause the tool 2 to engage and beat down the margin of the shoe, the shoe being suitably tipped on its longitudinal axis, either initially or 45 progressively, to cause the angle or opening between the upper and welt to be closed. The shoe is also, of course, moved longitudinally to cause not only the entire shank portion but also, if desired, other portions of the sole margin to be 50 similarly treated. The roll serves to guide the shoe as it moved lengthwise of the margin, so that the action of the beater is properly localized on the margin of the sole and protects the 55 lip from injury by accidental contact with the beater. When a shoe that is stitched aloft is to be treated, the machine is adjusted as indicated in Fig. 3, the shoe being located laterally with respect to the tool by the roll 36 which, being mounted on an axis substantially perpendicular to the sole, offers little resistance to movement of the shoe longitudinally. By holding the edge of the sole against the roll 36, the action of the 60 beater tool 2 is properly localized on the margin of the sole, and, by tipping the shoe as before, the margin of the sole is bent and beaten down to cause the crease between the upper and sole or welt to be closed. In some work it is desirable 65 to employ both the roll 20 and the roll 36 at the same time, the roll 20 then serving to protect the channel leaf while the roll 36 guides the shoe 70 75

to cause the action of the beater 2 to be properly localized.

Having thus described my invention, what I claim as new and desire to secure by Letters Patent of the United States is:

1. A machine of the class described having, in combination, a rotary beating tool having its periphery contoured to produce a beating action on a shoe brought in contact therewith, said tool being hollowed out on one of its side faces, and a guide roll partially housed in the hollow of the tool and having a lip projecting beyond the tool to engage the channel of the outsole of the shoe. 80 85

2. A machine of the class described having, in combination, a beating tool for treating the channeled outsole of a shoe, means for operating the tool, and a guide engaging the channel and arranged to yield upwardly to pressure of the shoe as it is brought into engagement with the beating tool. 90 95

3. In a machine for treating the marginal portions of the outsoles of boots and shoes, a beating tool, means for operating the tool, a rotary guide for the sole edge to localize the action of the tool upon the sole margin, and a yielding guard engaging the channel leaf to prevent injury to the leaf by the beating tool. 100

4. A machine of the class described having, in combination, a beating tool, means for operating the tool, a yielding guard for protecting the channel leaf of a sole while its margin outside of the leaf is being presented to the tool for its beating action, and means for guiding the shoe to localize the action of the beater upon the sole margin as the shoe is moved longitudinally in presenting the margin of the sole to the beating tool. 105 110 115

5. A machine of the class described having, in combination, a beating tool arranged to operate upon the bottom of a shoe, means for operating the tool, a long thin arm extending forwardly and upwardly, its inner end being adjustably fixed, and a guide roll arranged for rotation on the forward end of said arm in a plane substantially parallel to the acting face of the beating tool and fixed against bodily movement in said plane for determining the lateral position of the shoe to localize the action of the tool upon the margin of the sole, the arm yielding vertically 120 125 to upward pressure of the shoe on the guide roll. 130

6. A machine of the class described having, in combination, a beating tool for treating a shoe sole having a channel, means for operating the tool, and a yielding guide adjacent to the tool to 130 locate the shoe relatively to the tool and protect the channel leaf of the sole from engagement with the tool as the margin of the sole outside the channel leaf is presented to the tool to receive its beating action. 135

7. A machine of the class described having, in combination, a pounding tool, means for operating the tool, and a rotary guide roll adjacent to said tool and having a lip arranged to enter the channel of the outsole seam of a shoe. 140

8. A machine for closing the shanks of boots and shoes, having, in combination, a beating tool to treat the marginal portion of an outsole, means for operating the tool, means for guiding the shoe for the action of the tool, and yielding 145 means engaging the channel of the outsole to protect the channel leaf from injury by the tool.

9. A machine of the class described having, in combination, a rotary beating tool having its periphery contoured to produce a beating action 150

- on a shoe brought in contact therewith, said tool being hollowed out on one of its side faces, and a guide roll partially housed in the hollow of the tool and having a lip projecting beyond the tool 5 to engage the channel of the outsole of the shoe and a concaved periphery to receive and protect the inturned channel flap. 10. A machine of the class described having, in combination, a beating tool, means for operating the tool, and a guide roll adjacent to the tool and arranged for rotation on an axis inclined at approximately thirty degrees to the operating face of the beating tool. 11. In a machine for treating the marginal portions of the outsoles of boots and shoes, a beating tool, means for operating the tool, a guide for the sole edge to localize the action of the tool upon the sole margin, and an idle rotary guard roll engaging the channel leaf to prevent injury to the leaf by the beating tool. 12. A machine of the class described having, in combination, a beating tool, means for operating the tool, an upwardly yielding guard for protecting the channel leaf of a sole while its margin outside the leaf is being presented to the tool for its beating action, and a rotary guide roll engaging the sole edge to localize the action of the beater upon the sole margin as the shoe is moved longitudinally in presenting the margin of the sole to the beating tool. 13. A machine of the class described having, in combination, a beating tool arranged to operate upon the sole of a shoe, an upwardly and forwardly extending arm of thin vertical extent to enable it to yield upwardly, and a guide roll mounted on the forward end of said arm for determining, by engagement with the edge face of the sole, the lateral position of the shoe to localize the action of the beating tool on the margin of the bottom of the shoe sole, the roll carrying arm yielding to upward pressure of the shoe upon the roll when the shoe is tipped far enough for the shoe upper to engage the roll and permitting beating action of the tool upon the sole. 14. A machine of the class described having, in combination, a beating tool for treating the sole of a shoe, means for operating the tool, and a guard roll mounted adjacent to the tool for rotation independently of the tool upon an axis inclined to the axis of the tool and having a grooved periphery to cover and protect the channel leaf of the sole from engagement with the tool as the margin of the sole outside the channel leaf is presented to the tool to receive its beating action. 15. In a shoe shank beating and stitch rubbing machine the combination with a beating tool of a guide for work, said guide having an edge adapted to be guided along the angular shoulder of a channel flap at its juncture with the sole of a shoe, said guide being adjustable to various angles of inclination. 16. A shoe shank beating and stitch rubbing machine having a beating iron, and a guide for controlling the position of a shoe bottom pressed against said beating iron, said guide movable with relation to said shoe bottom along a line interspaced from the edge of the shoe sole, said guide being mounted independently of said beating iron, and being adjustable to various angular positions. 17. A machine of the class described having, in combination, a rotary beating tool having its periphery contoured to produce a beating action on the sole of a shoe brought in contact therewith, said tool being hollowed out on one of its side faces, and a guide partially housed in the hollow of the tool, said guide having a lip projecting beyond the tool to engage in the channel of the sole of the shoe.
